PROCESS FOR THE SWEETENING OF
HYDROCARBON OILSJohn H. McClintock, Cranford, N. J., assignor to
Standard Oil Development Company, a corpora-
tion of Delaware

Application April 26, 1941, Serial No. 390,530

2 Claims. (Cl. 196—33)

The present invention is concerned with the refining of mineral oils. The invention more particularly relates to a process for the removal of undesirable sulfur compounds from petroleum oils, and is especially concerned with an improvement in sweetening operations in which mercaptan compounds are converted to harmless disulfides, utilizing an alkali metal plumbite solution and free sulfur. The invention is particularly applicable in the treatment of petroleum oils boiling in the motor fuel boiling range employing the so-called "doctor" solution comprising a sodium plumbite solution. In accordance with the present process two stages are employed under conditions in which a relatively large amount of clean, fresh doctor is added in the secondary stage. A preferred modification of the process is to contact the feed oil with a relatively small critical amount of doctor solution in the initial stage, separate the oil and contact the same with a relatively large amount of doctor solution in the secondary stage.

It is known in the art to treat mercaptan-containing mineral oils, particularly mercaptan-containing petroleum oils, in various ways in order to remove the mercaptan compounds or to convert them into harmless disulfides. This is necessary since mercaptan materials render the oil sour and prohibit its commercial use. The usual method employed in the treatment of petroleum oils, particularly in the treatment of the petroleum oils boiling in the motor fuel boiling range, is to contact the oil under suitable conditions with a so-called "doctor" solution comprising an alkaline sodium plumbite solution.

The sodium plumbite reacts with the mercaptans to form oil-soluble lead mercaptides. These mercaptides are converted to oil-soluble alkyl disulfides and the lead removed from the treated oil as precipitated lead sulfide by treatment usually with free sulfur. For example, in the preparation of a doctor solution comprising a sodium hydroxide solution of sodium plumbite the usual practice is to employ a sodium hydroxide solution of less than about 15° Baumé, generally a solution having a concentration in the range from about 12° to 14° Baumé and to add thereto lead oxide. The common practice is to add sufficient lead oxide to saturate the solution. Any additional lead oxide added merely settles out. This reaction may be illustrated by the following equation:

Under these conditions when using, for example, 14° Baumé sodium hydroxide, the approximate concentration of lead oxide is 6.8 lbs. per bbl. (42 gallons) of sodium hydroxide solution. When solutions of this character are contacted with mercaptan-containing oils the mercaptan compounds are converted to soluble lead mercaptides. These soluble lead mercaptides are then reacted usually with free sulfur resulting in the formation of precipitated lead sulfides and alkyl disulphides. These reactions may be illustrated as follows:

This operation is not entirely satisfactory, since the doctor solution tends to cause emulsification difficulties which results in a relatively large loss of oil in the spent doctor solution. Furthermore, an appreciable amount of flocculant lead sulfide remains in the treated oil which is relatively difficult to remove. It has therefore been proposed that a sufficient excess of doctor solution be employed so as to secure the basic lead mercaptide in accordance with the following reaction:

The basic lead mercaptide when treated with sulfur results in the formation of alkyl disulfides and precipitated lead polysulfide, or basic lead sulfide. This may be illustrated by the following reaction:

This reaction, however, is not entirely satisfactory for several reasons, one of which is that a relatively large amount of doctor solution must be employed.

I have now discovered a process by which it is possible to remove the lead sulfide carry-over efficiently and to free the treated oil of the same completely. In accordance with my process the treated oil removed from the initial stage containing the flocculant lead sulfide is contacted in a secondary stage with a relatively large amount of fresh doctor solution completely free of lead sulfide, under conditions to remove the lead sul-

fide from the treated oil. The fresh doctor solution from the secondary stage is then recycled to the initial stage wherein conditions are adapted to remove the mercaptans from the oil. A desirable modification of my process is to treat the oil in an initial stage under conditions to form the basic lead mercaptide. The oil in a slightly acidic condition is removed from the initial treating zone and contacted in a secondary treating zone in contact with a relatively large volume of fresh doctor solution substantially completely free of lead sulfide, under conditions to convert the basic lead mercaptides to normal mercaptides. The process of my invention may be readily understood by reference to the drawing illustrating embodiments of the same.

For the purpose of description it is assumed that the feed oil comprises a mercaptan-containing feed oil boiling in the motor fuel boiling range. This oil is introduced into the system by means of line 1 and mixed with fresh alkali metal plumbite solution which is introduced by means of line 2. For the purpose of description it is assumed that the alkali metal plumbite solution is a doctor solution. The mixture is passed through mixing zone 3 under conditions to secure suitable contact between the respective streams. Sulfur is added by means of line 20. The mixture is passed into treating and separating zone 4 wherein a separation is made between the treated oil and the spent doctor solution. In one adaptation of the operation treating conditions in zone 4 are adjusted so as to secure the complete conversion of the mercaptans to the corresponding alkyl disulfides. The treated oil free of mercaptans and containing flocculant lead sulfide due to the inherent nature of the operation is withdrawn from zone 4 by means of line 7 and mixed with an additional quantity of fresh doctor solution which is introduced by means of line 8. This fresh doctor solution is substantially completely free of lead sulfide. The mixture is passed through mixing zone 9 and introduced into zone 10 wherein a separation is made between the treated oil and the fresh doctor solution added by means of line 8. The treated oil completely free of flocculant lead sulfide is removed by means of line 11 while the doctor solution containing the lead sulfide is removed by means of line 12 and recycled to the fresh feed in initial treating zone 4 by means of line 13. By operating as described in which a relatively large amount of fresh caustic free of lead sulfide is introduced into the secondary stage, a treated oil free of flocculant lead sulfide is removed from the secondary stage. When operating as described the fresh doctor solution is functioning in removing flocculant lead sulfide from the treated oil.

A preferred operation in accordance with the present invention is to adapt the treating conditions and the respective feed rates so that the lead mercaptides are present in zone 4 as the normal lead mercaptides. Thus, when sulfur is added, the normal lead mercaptides will react with the sulfur to precipitate lead sulfide and form alkyl disulfides. This mode of operation is secured by utilizing a relatively small amount of doctor solution in the initial treating zone. The spent doctor solution containing the lead as lead sulfide is withdrawn from zone 4 by means of line 5, passed to regeneration zone 21 and recycled to sodium plumbite storage 22 by means of line 23. The partially treated oil containing dissolved therein a relatively small amount of

unremoved mercaptans is withdrawn from zone 4 by means of line 7 and mixed with an additional relatively large quantity of fresh doctor solution which is introduced by means of line 8.

- 5 The doctor solution is substantially completely free of lead sulfide. The mixture is passed through mixing zone 9 wherein additional sulfur is added by means of line 24, under conditions to secure adequate contact between the respective streams. The mixture is passed into zone 10 in which a separation is made between the doctor solution and the treated oil. Temperature and pressure and the respective feed rates are adjusted in zone 10 so as to secure the formation of basic lead mercaptides which upon the addition of sulfur will result in the precipitation of basic lead sulfide. The spent doctor solution containing the precipitated basic lead sulfide and the carry-over lead sulfide from the initial treating zone is removed from zone 10 by means of line 12 and preferably recycled with the feed oil to the initial treating zone by means of line 13. However, under certain conditions it may be desirable to pass at least a portion of the spent doctor solution withdrawn from the secondary treating zone to regeneration zone 21 by means of line 25. The treated oil is withdrawn from the system by means of line 11 and handled as desired.

30 Although I do not wish to be restricted by the same it is my belief that the reactions involved are as follows:

In the above reactions the basic lead sulfide precipitated in the secondary zone will more readily separate and will not be carried over with the treated oil to any extent. Furthermore, the precipitation of the basic lead sulfide will substantially completely remove the carry-over flocculant lead sulfide from the initial zone.

The process of the present invention may be 60 widely varied. It is to be understood that the respective zones may comprise any suitable number and arrangement of units. The invention essentially comprises employing a relatively large amount of fresh doctor solution in a secondary 65 treating zone in order completely to remove flocculant lead sulfide from the oil in said zone. Doctor solution utilized in the secondary treating zone is then contacted with a feed oil in the initial treating zone under conditions to remove the mercaptans from the feed oil.

Although it is preferred completely to remove the mercaptans in the initial treating zone, under certain conditions it may be desirable to utilize a relatively small amount of doctor solution in 75 the initial treating zone so that lead sulfide is

precipitated therein and that the partially treated oil removed from the initial treating zone contains unreacted mercaptans. If this type of operation be employed, it is desirable that at least 50% of the total mercaptans present in the feed oil be removed in the initial treating zone, preferably that at least 75% of the same be removed in said zone.

The partially treated oil containing carry-over lead sulfide and free mercaptans is then contacted with an appreciable excess of doctor solution and sulfur so that basic lead sulfide is precipitated in the secondary zone. Under these conditions the basic lead sulfide precipitated will completely free the oil of flocculant lead sulfide. Operating conditions, in general, are adapted completely to free the treated oil of mercaptans and lead sulfide. The spent solution containing the basic lead sulfide is recycled to the initial treating zone with the feed oil. A particularly desirable operation comprises introducing fresh doctor solution into the oil stream entering both the initial and secondary treating zone and to split the spent doctor solution withdrawn from the secondary treating zone, recycling a portion of the same with the feed oil and regenerating a portion of the same.

Although the operation may be adapted for the removal of mercaptans from any feed oil, it is particularly suitable for the removal of these sulfur compounds from petroleum oils boiling in the motor fuel boiling range. A preferred solution comprises an alkaline sodium plumbite solution. The quantity used per volume of oil contacted will vary considerably, depending upon the concentration of the plumbite solution, the type of oil being treated, and the concentration and character of mercaptan compounds present.

What I claim as new and wish to protect by Letters Patent is:

1. Continuous process for the sweetening of hydrocarbon oils containing mercaptans which consists essentially in continuously contacting said oil in a sweetening zone with a doctor solution comprising an alkali metal plumbite solution and

5 with sulfur, under conditions to convert all the mercaptans into disulfides and to precipitate lead sulfide, continuously separating the resultant spent doctor solution containing most of the precipitated lead sulfide from the resultant sweetened oil containing a small amount of flocculant precipitated lead sulfide regenerating the spent doctor solution to convert lead sulfide into plumbite solution, continuously contacting the sweetened oil containing flocculant lead sulfide in a 10 clarifying zone with the regenerated doctor solution free from lead sulfide, continuously separating the resultant clarified sweetened oil from the regenerated doctor solution containing the lead sulfide removed from the sweetened oil in the clarifying zone, and continuously recycling said regenerated doctor solution to the original sweetening zone for contacting additional fresh oil.

2. Continuous process for the sweetening of a 15 petroleum naphtha of the motor fuel boiling range containing mercaptans which consists essentially in continuously contacting said naphtha in a sweetening zone with a doctor solution comprising a sodium plumbite solution and with sulfur, under conditions to convert all the mercaptans into disulfides and to precipitate lead sulfide, continuously separating the resultant spent doctor solution containing most of the precipitated lead sulfide from the resultant sweetened naphtha containing a small amount of flocculant precipitated lead sulfide, regenerating the spent doctor solution to convert lead sulfide into plumbite solution, continuously contacting the sweetened naphtha containing flocculant lead sulfide 20 in a clarifying zone with the regenerated doctor solution free from lead sulfide, continuously separating the resultant clarified sweetened naphtha from the regenerated doctor solution containing the lead sulfide removed from the sweetened naphtha in the clarifying zone, and continuously recycling said regenerated doctor solution to the original sweetening zone for contacting additional fresh naphtha.
